UNITED STATES PATENT OFFICE

2,434,664

SEALING-IN MACHINE

Frank J. Malloy, deceased, late of University Heights, Ohio, by Catherine A. Malloy, executrix, University Heights, Ohio, assignor to General Electric Company, a corporation of New York

Application November 9, 1942, Serial No. 465,008

5 Claims. (Cl. 49—2)

1

The present invention relates to sealing apparatus for electric lamps and the like, and is particularly useful for fusing the flared vitreous stem tube of a mount for a fluorescent lamp into the open end of the tubular vitreous bulb thereof.

One object of the invention is to provide apparatus for sealing the flared glass stem of electric lamps and similar devices into the open mouth of the bulb of said devices in a ready and satisfactory manner. The apparatus provides for the sealing of the glass stem, which supports the leading-in wires and other essential parts of the device, to the glass bulb both economically and at high speed. The apparatus is particularly adaptable to seal together the usual commercial stems and bulbs which vary slightly in form.

Another object of the invention is to provide apparatus for sealing a stem into a bulb wherein a minimum of each of these parts is fused and reshaped by said operation. The sealing of fluorescent lamps, for instance, must be restricted to a relatively narrow end section at each end of the bulb as these sections must be enclosed within small flat bases.

Still another object of the invention is to provide apparatus for sealing a stem into the open mouth of a bulb, which apparatus facilitates the shaping of the sealed portion and, in the case of a double ended bulb, the control of the overall length thereof. The sealing operation provides an outwardly extending ridge or bead at the end of the bulb which permits the more satisfactory fastening of the base thereto, whereas the control of bulb length permits the lamps to be used in standard size lighting fixtures and arranged in end-to-end relation satisfactorily.

Other objects and advantages of the invention will appear from the following detailed description of a species thereof and from the drawing.

In the drawing, Fig. 1 is a plan view, partially broken away, of a sealing machine embodying the invention; Fig. 2 is a vertical section through a head of said machine located at the unloading station; Figs. 3 and 4 are plan and perspective views respectively of the bulb holding jaws of the heads; Figs. 5 and 6 are perspective views of apparatus for raising the mount-shaping means at station H, J and L; Fig. 7 is a perspective view of the upper end of the spindle of alternate heads with a mount partially inserted therein; Fig. 8 is a perspective view of a modified spindle for the heads; Fig. 9 is a perspective view of modified apparatus for actuating the seal-shaping means; and Fig. 10 is a vertical section through the modified spindle shown in Fig. 8 and a corresponding

2

section through a mount and a bulb end in sealing relation thereto and midway in the course of the sealing operation.

The apparatus shown in the drawing comprises fifteen heads 11 located about the periphery of the turret 12 which heads 11 carry the mount 13 and bulb 14 to each of a corresponding number of work stations, A to Q, during the course of rotation of the turret 12. The mount 13 and bulb 14 are placed in the head 11 by an operator located adjacent stations A and B. The mount illustrated in the drawing is of the type shown in application Serial No. 368,021, John Flaws, filed November 30, 1940, now Patent No. 2,312,245, and assigned to the assignee of this application.

The turret 12 is indexed in a counterclockwise direction and, usually, the operator places the mount 13 on the upper end of the spindle 15 while the head 11 is located at station A, and inserts the bulb 14 in the holder 16 thereof at station B. The mount 13 is placed in the proper location in the head 11 by inserting the exhaust tube 17 and leading-in wires 18 and 19 into the axial opening or bore in the pin or cap 20 on the upper end of the spindle 15 and then pushing said mount 13 down until the flared stem tube 21 thereof rests on the head of the pin 20. At such times the end of exhaust tube 17 is confined within the restricted portion 20' of the opening in the lower portion of the pin 20 and the flared stem tube 21 rests on the conical top or head of said pin 20.

The bulb 14 is inserted by, first, pressing it into engagement with the V-grooves 22' in jaw 22 (Figs. 3 and 4) and a corresponding V-groove in the guide 23 (Fig. 2) of the holder 16, and then sliding it down until the open lower end butts against the rim of the flare portion of the stem tube 21 very much as shown in Fig. 9. The handle 24 is then moved to the right to the position shown in Figs. 3 and 4 so that the movable jaw 25 is caused to engage and grip said bulb 14. The guide 23 and jaws 22 and 25 are mounted at spaced points on the rod 26 which extends upwardly from the flanged portion 27 of the spindle 15, and prevent the bulb 14 from shifting out of position during the indexing movements of the turret 12. The jaws 22 and 25 are mounted between the upper and lower plates 28 and 29 extending from the bracket 30 on the rod 26 and are pivotably mounted on the pins 31 and 32 respectively.

When the bulb 14 is introduced into the head, the roller 33 on the pin 34 holding the handle 24 is located against the shoulder 35 of jaw 25 and the contraction force of the spring 36 ex-

tending between pin 34 and the post 37 causes said jaw 25 to be held to its open position as shown at stations A and B. At such times the edge 38 of said jaw 25 rests against the collar 39 of pin 40. When the jaws 22 and 25 are closed, the roller 33 occupies the position shown in Figs. 3 and 4 and the contracting force of the spring 36 keeps the jaw 25 turned so that the rubber pad 41 engages the bulb 14, and the extending portion 42 (Fig. 3) engages the screw 43 turning the jaw 22 into engagement with the bulb 14. The roller 33 and pin 34 are supported by the arm 44 which swings in the slot 45 in the bracket 30 and which is slotted for the pin 37 so that it may move in or out as required. Should the bulb 14 vary somewhat from normal size, the engagement of the extending portion 42 of jaw 25 and the screw 43 in jaw 22 will cause both jaws 22 and 25 to close correspondingly and said bulb 14 will always be directly on the center of the head 11.

Following stations A and B is an idle station C which can if desired be used by the operator for loading the head 11.

In indexing to station D, the next in order, the head 11 first passes from engagement with the track 47 (located below the turret 12) which has prevented it from turning away from the operator and then passes into engagement with the moving chain 48 which rotates it. The track 47 (Figs. 1 and 2) is a stationary member lying parallel to the path of movement of the head 11 through stations P, Q, A, B and C and comprises inner and outer rails 49 and 50 respectively which are mounted on brackets 51 extending from the stationary frame (not shown) of the machine and which define a path along which the roller 52 of the head 11 must travel. The roller 52 is mounted on a post extending from the lower face of the fly wheel 53 which is attached to a portion of the spindle 15 below the turret 12 and is so positioned that the bulb holder 16 is held in a position accessible to the operator. The chain 48, on the other hand, has motion in a counter-clockwise direction about the machine which causes it to pass to the sprocket 54 of the head 11 at station D and to engage corresponding sprockets of many of the other heads 11, the driven sprocket 55 and the idler sprockets 56, 57 and 58. In this particular instance, sprocket 55 is turned by the main driving means (not shown) of the machine and cooperates with sprockets 57 and 58 to direct the chain 48 away from the heads 11 at loading and unloading stations A, B, C and P, Q respectively where the head 11 is held by track 47. Sprocket 56 is part of means for keeping the chain 48 taut and is mounted on the arm 59 which is biased by the spring 60 so as to pull the chain 48 out of its normal path of movement. An outwardly extending portion of the frame 61 of the machine supports the shaft holding the driven sprocket 55, the posts holding idler sprockets 57 and 58 and the arm 59 supporting sprocket 56.

Station D and station E, the next in order, are similar work stations in that both have pairs of burners 62 and 63 directing soft flames against the exposed rim of the flared stem tube 21 and two to three inches of the lower end of the bulb 14. These burners 62 and 63 are, on occasion, used in combination with a third pair of burners at the next station F and gradually raise the temperature of the glass parts until they can take the shock of the hard sealing fires at subsequent stations without cracking.

Stations F, G, H, J, K, L and M are occupied by the sealing burners 64 which in this particular instance comprise a group of four burners directing very sharp hard flames against the exposed rim of the flared stem tube 21 and the immediately adjacent end portion of the bulb 14. These burners 64 may use a natural gas and oxygen mixture of considerable heating effect and heat the flared stem tube 21 to such an extent that its rim portion becomes soft and plastic while the head 11 is at station H.

The softening of the glass parts permits the succeeding operation, which takes place as the head 11 is about to index from station H, to be brought about as a pusher means in the form of the sleeve 65 then moves up momentarily against the outer rim of the stem tube 21 causing it to be bent and worked up into more intimate contact with the edge of the bulb 14. The rim of the bulb 14 may be upset slightly by the action of the sleeve 65 which is sufficiently powerful to bring these parts together should the rim of either the stem tube 21 or bulb 14 be incorrectly positioned through improper alignment of the parts in the head 11 or should inaccuracies in the form of said parts exist. The sleeve 65 has an inwardly bevelled upper end 65' and is connected to the tube 66 within the hollow center of the spindle 15 by the bolts 67-67 (Fig. 2) which normally rest at the bottom of the slots 67' in the spindle 15 in which they are located as shown because of the downward pressure exerted by the expansion force of the spring 68 which is located between the spindle 15 and the end of tube 66.

The upward motion is imparted to the sleeve 65 by apparatus (Figs. 1 and 5) mounted on the frame 61 of the machine below station H which apparatus comprises a post 69 located directly below the lower end of tube 66; a platform 70 holding said post 69; a vertically disposed shaft 71 supporting said platform 70; and the system embracing link 72, arm 73, shaft 74, arm 75, link 76 and lever 77. The cam 78 on the main drive shaft 80 engages the roller 81 on the lever 77 turning it about the post 82 extending from frame 61 of the machine and through the various parts of the system causes the shaft 71 to be moved vertically in the arms of the bracket 83 so that the platform 70 is raised and the end of the post 69 is caused to engage and raise the tube 66 to a definite height. During the period of movement, the shaft 74 of the actuating system turns in the arm 84 supporting it, and the bolts 67-67 connecting the sleeve 65 and the tube 66 slide vertically in the slots 67' in the spindle 15. The arm 84 is a stationary member which is attached to a portion 83' of the bracket 83 located about a lower portion of shaft 71. The sleeve 65 remains in the up position for a relatively short time in order to cool the heated glass parts as little as possible and is normally adjusted to produce a .030 inch upward displacement of the rim of the stem tube 21. In some instances it may be desirable to control the gripping force of the holder for the bulb 14 (for example, by using a weaker spring 36) so as to permit the bulb 14 to move upward therein when the rim of the bulb 14 is not sufficiently plastic to be displaced the full amount of the movement of the sleeve 65.

The rim of the bulb and the stem tube 21 continue to be heated at station J and finally, as the head 11 is about to be indexed therefrom, are further worked and upset by a second momentary upward movement of the sleeve 65. At this station the sleeve 65 is actuated by the move-

ments of the post 85 which is mounted on an extension of the platform 70; however, the post 85 is adjusted to raise the sleeve 65 .010 inch higher than it is raised at station H so as to assure positive contact and wetting of the rims of the bulb 14 and stem tube 21. This operation also upsets the rim of the bulb 14 until it forms an annular ridge 86 about the end of the lamp much the same as shown in Fig. 2. The mechanical working of the bulb 14 and stem tube 21 by the sleeve 65 at stations H and J causes the entire periphery of the rim portions thereof to be either sealed together or to be in very intimate contact with each other during the interval these parts are treated by the very hard high temperature fires of the burners at the succeeding stations and prevents said fires from developing openings between the parts. This method of operation is particularly desirable as the pressure of the sealing fires is so great as to enlarge any opening existing between the rim of the stem tube 21 and the bulb 14 rather than allow it to close by the natural flow of said parts.

At station K and stations L and M, the next in order, the burners continue to heat the adjacent portions of the bulb 14 and stem tube 21 so that the entire wall thickness of the seal is securely fused together. At station L the sleeve 65 is again raised into contact with the fused parts but in this particular instance its function is to correct any sagging that may have taken place in the seal and to upset it slightly so that the ridge 86 is slightly enlarged. This latter action of the sleeve 65 raises it .010 inch higher than at station J and is produced by the apparatus shown in Figs. 1 and 6 comprising post 87, platform 88, shaft 89, link 90, arm 91, shaft 92, arm 93, link 94, lever 95, roller 96 and cam 97. The rotation of the main drive shaft 80 on which the cam 97 is mounted causes the movement of the lever 95 to turn on the post 82 and indirectly the vertical actuation of the post 87 and platform 88. The shaft 89 moves in upper and lower portions of the bracket 98 which is mounted on the frame 61 and which holds the arm 99 supporting the shaft 92. The lamp now appears as shown in Fig. 2 having a mount 13 sealed in one end of the bulb 14.

Station N is occupied by a pair of burners 100 directing soft flames against the seal and the adjacent part of the bulb 14 as is station O although the burners at this latter station are not shown. These burners have an annealing effect on the seal and adjacent parts of the lamp and reduce the rate of cooling to such an extent that the lamp can, after leaving these stations, be allowed to cool in open air without incurring detrimental strains.

The indexing movement advancing the head 11 beyond station O carries the sprocket 54 away from the chain 48 which has caused it to rotate in the preceding stations occupied by the heating fires and advances the head 11 to a point where roller 52 enters between the inner and outer rails 49 and 50 of the track 47 so that the head 11 stops rotating and the bulb holder 16 faces the periphery of the machine.

Station P is an idle station in which the lamp is allowed to cool to a point where it can be handled without injury.

Station Q, the last in the series completing one revolution of the machine, is the unloading station and it is while the head 11 is located here that an operator opens the jaws 22 and 25 of

the bulb holder 16 by swinging handle 24 to the left and removes the lamp from the machine.

The fluorescent lamp is now only partially complete as a mount 13 is sealed in one end of the bulb 14 and the other remains open to the atmosphere. The mount that is sealed in this open end of the bulb 14 may have the same general construction as that now attached to the bulb 14 but usually does not have an exhaust tube or has only a short sealed tube 17 in place thereof as shown in Fig. 7 since the exhaust tube 17 of mount 13 is sufficient to permit the exhausting and filling of the lamp. If a mount having a full length exhaust tube is to be sealed in the open end of the bulb 14, said bulb 14 can be turned end for end and reinserted into the above described head 11 of the machine or into a duplicate head of another sealing machine of the same construction.

However, if the mount does not have an exhaust tube or has only a short sealed tube 17 in place thereof difficulty may be experienced locating the mount directly at the center of the sealing head 11. It is preferred in such cases that the pin or cap 101 has an upstanding lip 102 (as shown in Fig. 7) over which the tubular portion 103 of the stem tube can be placed to locate the mount thereon. Alternate heads 11 of the present machine are equipped with pins 101 of this type and the mount and bulb assembly usually taken from the machine at station Q is allowed to pass on to station A where it is removed by the loading operator and reinserted in the head 11 at station B. In this instance the two operators co-operate in servicing the machine; the operator opposite station Q inserting mounts first with long and then short exhaust tubes in alternate heads 11 appearing at station A and removing the completed lamp at station Q; and the operator opposite stations A and B inserting open ended bulbs 14 in the heads holding long exhaust tubes at station B, removing the bulbs having a mount sealed over one end from the heads at station A and, after turning them end for end, reinserting them at station B. In such an arrangement, alternate heads 11 are carrying the bulb 14 through the operations which seal the mount over one end thereof whereas the heads in between are carrying a bulb 14 already closed at the upper end through operations which seal a mount over the remaining open end.

The sealing heads 11 may be modified in other ways. As shown in Figs. 8 and 10, they may have a heat insulating collar 105 on the upper end of the spindle 15 and a differently formed mount support pin 106 and pusher means or sleeve 107. The collar 105 is made of asbestos and serves to reduce the conduction of heat from the mount support pin 106 so that it and the central portion of the stem tube 21 will be raised to a high temperature during the sealing operation. In this way the development of detrimental strains in the unfused portion of the stem tube 21 is reduced. The longitudinally extending holes 108 in the laterally extending head 106 of the mount pin 106 permit the heated gases passing under said head 106 to engage and heat the central portion of the overlying flange of the stem tube 21 causing a more gradual temperature gradient therein. The sleeve 107 in this instance has greater length than in the prior instance and presents the work surface 107' in position to engage the rim of the stem tube 21. The work surface is serrated to

allow the sealing fires to pass under the rim of the stem tube 21.

The modification of the machine disclosed in Fig. 8 can operate satisfactorily in combination with the apparatus already described, but the modified sleeve actuating means shown in Fig. 9 permits greater flexibility of operation which is required to receive the full benefits of said modification and permits a slight increase in the heating period of the machine. This modified sleeve actuating means comprises the track 112 which is mounted below the turret 12 on the frame of the machine in a position to function as a support for the tube 66 for its entire path of travel. The indexing motion of the turret 12 causes the tube 66 to slide along the track 112 which as applied to the modifications shown in Fig. 8 has a constant level from station A through station G as indicated and which drops $\frac{1}{2}$ inch between stations G and H to lower the sleeve 107. This vertical actuation of the sleeve 107 separates it from the rim portion of the mount 13 as said rim portion is held by the bulb 14 because it is partially sealed to it at this time and allows the sealing fires to pass under the rim of the stem tube 21 and up through holes 193 in the head 186' of the mount pin 106 to heat said stem tube 21 more completely. Should the above actuating means be used in combination with the sealing head 11 shown in Fig. 2, the track 112 will not be provided with the drop between stations G and H since the sleeve 65 is separated from the stem tube 21 at this time and sufficient space is provided to allow the sealing fires to reach the outer rim portion of the stem tube 21.

At station H of the modification shown in Fig. 9, the tube 66 is located over an opening in the track 112 and the upward movement of the sleeve 65 (or sleeve 107) is produced by a corresponding movement of a pin 113 through said opening and into engagement with the end of tube 66. The pin 113 is mounted on a lever 114 pivoted on the pin 115 held by the bracket 116 and is actuated by the downward pull of the weight 117 when the bolt 118 and the push rod 119 are lowered from engagement with the end of said lever 114. The operations of the push rod 119 is, in turn, controlled by the form of the cam 120 on the main drive shaft 88 of the machine which is engaged by the roller 121 on the lower end thereof and is produced by the expansion force of the spring 122 located between bracket 123 and the collar 124 on said push rod 119. Brackets 116 and 123 are stationary members fastened to the frame (not shown) of the machine. In this particular instance the extent to which the stem tube 21 and the rim of the bulb 14 is worked depends on the plastic or heated condition thereof as the pressure of the sleeve 65 (or sleeve 107) is limited to the effective force of the weight 117. If greater or less pressure is desired on the stem tube 21 at this station, the weight 117 is moved either away from or nearer the pivot pin 115 on lever 114. The operation of the sleeve 65 (or sleeve 107) is momentary and the tube 66 is lowered again into contact with the track 112 before the head is indexed to the next station.

In the course of the index from station H to station J, the tube 66 slides to a lower level of the track 112, in this instance $\frac{3}{8}$ inch below the former level thereof, so as to expose the center of the stem tube 21 more fully to the heat of the fires.

Further actuations of the sleeve 65 (or sleeve 107) occur during the indexing movements of the

head 11 from stations J to K and from K to L and are brought about by raised portions 125 and 126 of the track 112 which cause the rim of the stem tube 21 to be worked up .010 and then .020 inch higher than the maximum permitted at station H. These operations correspond to those taking place at stations J and L in the apparatus shown in Fig. 1 and work the rims of the stem tube 21 and the bulb 14 tightly together so that a very good seal of the desired form results. Slightly higher rates of operation are also permissible with the use of the modified mechanism in Fig. 9 as the above movements of the sleeve 65 (or sleeve 107) occur during the indexing movements of the head 11 and do not disturb the application of the heating fires to the stem tube 21 and bulb 14.

Obviously still other adjustments of the sleeve 65 (or sleeve 107) can be provided at any point along the path of movement of the head 11 by providing a raised portion in the track 112, but the preferred method of operation consists in allowing the sleeve 65 (or sleeve 107) to remain at the lowermost position until the lamp is removed and the head 11 passes station Q. Between stations Q and A a rise 127 in the track 112 carries the sleeve 65 (or sleeve 107) to the upper position in which it is located when the mount 13 and bulb 14 are loaded in the head 11.

What is claimed as new and desired to secure by Letters Patent of the United States is:

1. A sealing-in machine comprising the combination of a rotatable turret, a head mounted at the periphery of said turret and carried thereby to a plurality of stations, said head comprising a vertical spindle carrying a support for the flanged stem of a mount, a holder for a glass bulb above and in register with the mount support, an upsetting sleeve surrounding the upper end of said spindle and mounted for vertical movement with respect to said mount support, means for fusing said stem and bulb together, and actuating cam mechanisms at a plurality of stations arranged to raise said upsetting sleeve predetermined successive amounts into abutting engagement with the fused joint between said stem and bulb to compress and upset said joint, at least the cam mechanism at one station being arranged to raise the upsetting sleeve substantially higher than it is raised by the corresponding cam mechanism at a preceding station.

2. A head for a sealing-in machine comprising a vertical hollow spindle mounted for rotation about its axis, a mount pin in the upper end of said spindle for supporting the flanged stem of a mount, a holder for a glass bulb mounted above and in register with said mount pin and supported from said spindle, an upsetting sleeve surrounding the upper end of said spindle and movable vertically therewith into and out of abutting engagement with the rim of a stem on said mount pin, a sleeve actuating tube member mounted within said spindle and extending downwardly therethrough and vertically movable therein, and connector means connecting said upsetting sleeve and tube member together, said spindle being vertically slotted to receive said connector means.

3. A head for a sealing-in machine comprising a vertical hollow spindle mounted for rotation about its axis, a mount pin in the upper end of said spindle for supporting the flanged stem of a mount, said mount pin having a laterally extending head portion with holes extending longitudinally and vertically therethrough and adapted to support the mount by engagement of the up-

per surface of the pin head with the surface of the stem flange so that said flange overlies said holes, a holder for a glass bulb mounted above and in register with said mount pin and supported from said spindle gas burners located adjacent the upper end of said spindle and adapted to direct flames at the rim portions of the flanged stem and bulb to fuse said portions together and to apply heat upward through the holes in said pin head to heat the stem flange and reduce the strains therein, an upsetting sleeve surrounding the upper end of said spindle and movable vertically therealong into and out of abutting engagement with the rim of a stem on said mount pin, a sleeve actuating tube member mounted within said spindle and extending downwardly therethrough and vertically movable therein, and connector means connecting said upsetting sleeve and tube member together, said spindle being vertically slotted to receive said connector means.

4. A head for a sealing-in machine comprising a vertical hollow spindle mounted for rotation about its axis, a mount pin in the upper end of said spindle for supporting the flanged stem of a mount, a holder for a glass bulb mounted above and in register with said mount pin and supported from said spindle, an upsetting sleeve surrounding the upper end of said spindle and movable vertically therealong into and out of abutting engagement with the rim of a stem on said mount pin and having its upper edge serrated, a sleeve actuating tube member mounted within said spindle and extending downwardly therethrough and vertically movable therein, and connector means connecting said upsetting sleeve and tube member together, said spindle being vertically slotted to receive said connector means.

5. Apparatus for sealing the rim portion of the flange on the stem tube of a mount to the rim of the open end of a bulb comprising a spindle, 40

a pin in the upper end of said spindle having a laterally extending head portion with holes extending longitudinally and vertically therethrough adapted to support said mount by engagement of the upper surface of the pin head with the surface of the stem tube flange so that said flange overlies said holes, burners located adjacent the upper end of said spindle and adapted to direct flames against the rim portion of the mount and bulb to fuse said portions together and to apply heat upwardly through the holes in the pin head to heat the stem tube flange and reduce the strains therein, an upsetting sleeve member surrounding the upper end of said spindle, and means mounting said sleeve member for vertical reciprocation to work the rim portion of the mount flange into intimate contact with the rim of the bulb.
